UNITED STATES PATENT OFFICE.

FRANK P. PFLEGHAR, OF NEW HAVEN, CONNECTICUT, ASSIGNOR TO
ENGLISH & MERSICK, OF SAME PLACE.

BRAKE-LEVER.

SPECIFICATION forming part of Letters Patent No. 503,385, dated August 15, 1893.

Application filed May 1, 1893. Serial No. 472,471. (No model.)

To all whom it may concern:

Be it known that I, FRANK P. PFLEGHAR, of New Haven, in the county of New Haven and State of Connecticut, have invented a new Improvement in Brake-Levers; and I do hereby declare the following, when taken in connection with accompanying drawings and the letters of reference marked thereon, to be a full, clear, and exact description of the same, and which said drawings constitute part of this specification, and represent, in—

Figure 1, a view in side elevation of a brake-lever constructed in accordance with my invention, and shown as combined with a segmental rack; Fig. 2, a view of the same parts in vertical central section.

My invention relates to an improvement in levers for carriage-brakes, the object being to produce a compact and convenient device in which the spring-actuated pawl co-operating with the segmental rack of the brake, is housed within the upper end of the lever, and thus protected, and obscured from view.

With these ends in view, my invention consists in certain details of construction and combinations of parts as will be hereinafter described and pointed out in the claims.

In carrying out my invention, I employ a segmental rack A, of ordinary construction, and designed to be fixed to the frame-work of a carriage, or other vehicle, in the usual manner. With this rack I employ a brake-lever, which is hung to swing on a fulcrum or center, considerably below it. As herein shown, I have represented only the upper portion B, of the said lever, and no more is necessary, for the lower portion of it is of ordinary construction, and is generally made by a black-smith, while the portion of the brake shown is of higher finish, and supplied to the trade, the upper portion B, shown, being welded to the lower portion, in the ordinary manner, well known to all skilled in this art. The upper portion B, of the lever, is constructed about midway of its length, with a transverse slot C, through which the segmental rack A, passes, and which is intersected by the lower end of a longitudinal chamber D, circular in transverse section, and extending thence through the top of the portion B of the lever. This chamber receives the pawl E, the nose of

which engages with the teeth of the rack A, the said pawl being constructed with a stem F, which projects out of the chamber D, and beyond the top of the portion B of the lever. 55 The projecting end of the said stem is constructed with a head F', by means of which it is connected with a hand-lever G, secured by a horizontal pin or pivot H, to a lug or arm I, offsetting from the upper end of the portion 60 B, of the lever. A spiral spring J, encircling the stem F, and located within the chamber D, abuts at its lower end against the upper end of the pawl E, while its upper end abuts against the lower end of a sleeve K, inserted into the 65 upper end of the chamber D, forming a bearing for the stem F, and secured in place by means of a transverse pin L, which enters a socket formed in part in the lever, and in part in the periphery of the sleeve. It will be understood that when the hand-lever G is depressed, the pawl will be lifted against the 70 force of the spring J, and its nose disengaged from the teeth of the rack A, after which the lever may be swung back and forth with respect to the rack, as desired. Just as soon as the hand-lever is relieved of pressure, however, the spring J, restores the pawl to engagement with the teeth of the rack. It will be observed that the pawl and its spring are 75 concealed, and protected within the chambered upper portion of the lever, with an obvious gain of security and appearance, for heretofore in brake-levers of the kind shown and described the pawl and spring have been connected with the upper end of the lever, but located outside of the same, where they were 80 not only liable to be deranged, but also presented a clumsy and unsightly appearance. Under my improved construction the pawl 85 is located entirely within the lever, for although it normally projects into the transverse slot thereof, it does not extend out of the said slot.

It is obvious that in carrying out my invention, the details of construction shown and described may be departed from; thus, the hand-lever might be arranged to stand upright, and substantially in line with the brake-lever. I would therefore have it understood 90 that I do not limit myself to the exact construction herein shown and described, but

hold myself at liberty to make such changes and alterations as fairly fall within the spirit and scope of my invention. I am aware, however, that a chambered brake-lever having a pawl operated through its inside from its upper end and co-operating with a segmental rack, is old, and I do not, therefore, claim that construction broadly.

Having fully described my invention, what I claim as new, and desire to secure by Letters Patent, is—

1. A lever for carriage-brakes, having a transverse slot to receive a segmental rack over which the lever moves, and a longitudinal chamber extending from the upper end of the lever down into the said slot, a pawl for engagement with the rack, located in the said chamber, and having a shank projecting out of the upper end thereof, a spring located within the chamber, and operating upon the pawl to throw it toward the rack, and a handle-lever connected with the projecting end of the shank of the pawl, and pivoted to the upper end of the said lever within which the said pawl is entirely located, substantially as described.

2. A lever for carriage-brakes, having a transverse slot formed in it to receive a segmental rack over which the lever moves, and a longitudinal chamber formed in the upper end of the lever, and at its lower end intersecting the said slot, a pawl for engagement with the rack, located in the said chamber, and having a shank projecting out of the upper end of the same, a sleeve located in the upper end of the chamber and surrounding the shank of the pawl for which it forms a bearing, a spring interposed between the pawl and the inner end of the said sleeve, and arranged to move the pawl toward the rack, and a pivotal hand-lever connected with the projecting outer end of the shank of the pawl and pivoted to the said lever, within which the said pawl is entirely located substantially as described.

In testimony whereof I have signed this specification in the presence of two subscribing witnesses.

FRANK P. PFLEGHAR.
